Primary Examiner—Brian N. Vinson

[57] **CLAIM**

The ornamental design for a programmable integrated communications terminal, as shown and described.

DESCRIPTION

FIG. 1 is an front isometric/perspective view of the programmable integrated communications terminal (PICT™) of the present invention;

FIG. 2 is a top plan view of the programmable integrated communications terminal of FIG. 1;

FIG. 3 is a front elevation view of the programmable integrated communications terminal of FIG. 1;

FIG. 4 is a bottom plan view of the programmable integrated communications terminal of FIG. 1;

FIG. 5 is a right side elevation view of the programmable integrated communications terminal of FIG. 1;

FIG. 6 is a rear elevation view of the programmable integrated communications terminal of FIG. 1; and,

FIG. 7 is a left side elevation view of the programmable integrated communications terminal of FIG. 1.

The broken-line disclosure in the views is for illustrative purposes only and forms no part of the claimed design.
